DESIGN FOR A FOOD VENDING MACHINE

Raymond G. F. Loewy, New York, N. Y., assignor to New York Lunchmaster Corp., New York,
N. Y., a corporation of New York

Application March 24, 1938, Serial No. 76,064

Term of patent 3½ years

To all whom it may concern:

Be it known that I, Raymond G. F. Loewy, a citizen of the United States, residing in the Borough of Manhattan, city, county, and State of New York, have invented a new, original, and ornamental Design for a Food Vending Machine, of which the following is a specification, reference being had to the accompanying drawing, forming a part thereof, in which:

Fig. 1 is a perspective view of a food vending machine showing my new design; and

Fig. 2 is a side elevational view thereof. The dominant feature of my design consists in the parallel arrangement in the door of a refrigerator of two horizontal series of doors with a corresponding series of windows arranged above and in vertical alignment with each series of doors, as shown.

I claim:

The ornamental design for a food vending machine, substantially as shown and described.

RAYMOND G. F. LOEWY.
